US0D1066398S

(12) **United States Design Patent** (10) **Patent No.:** **US D1,066,398 S**
(45) **Date of Patent:** **** Mar. 11, 2025**

(54) **DISPLAY SCREEN OR PORTION THEREOF
WITH GRAPHICAL USER INTERFACE**

(71) Applicant: **Apple Inc.**, Cupertino, CA (US)

(72) Inventors: **Guillaume P. Barlier**, San Mateo, CA (US); **Lisa K. Forssell**, Palo Alto, CA (US); **Joseph D. Gardner**, San Francisco, CA (US); **Aurelio Guzmán**, San Jose, CA (US); **Jason D. Rickwald**, Santa Cruz, CA (US); **Christopher J. Romney**, San Francisco, CA (US); **Nicolas V. Scapell**, London (GB); **Christopher I. Wilson**, San Francisco, CA (US); **Giancarlo Yerkes**, Menlo Park, CA (US)

(73) Assignee: **Apple Inc.**, Cupertino, CA (US)

(**) Term: **15 Years**

(21) Appl. No.: **29/853,809**

(22) Filed: **Sep. 19, 2022**

Related U.S. Application Data

(63) Continuation of application No. 29/707,733, filed on Sep. 30, 2019, now Pat. No. Des. 964,458.

(57) **CLAIM**

The ornamental design for a display screen or portion thereof with graphical user interface as shown and described.

DESCRIPTION

The file of this patent contains at least one drawing/photograph executed in color. Copies of this patent with color drawing(s)/photograph(s) will be provided by the Office upon request and payment of the necessary fee.

The FIGURE is a front view of a display screen or portion thereof with graphical user interface showing the claimed design.

The outer dashed broken lines in the FIGURE show a display screen or portion thereof, and form no part of the claimed design.

The dot-dash broken lines in the FIGURE and the faded areas within the dot-dash broken lines show portions of the graphical user interface that form no part of the claimed design.

**1 Claim, 1 Drawing Sheet
(1 of 1 Drawing Sheet(s) Filed in Color)**
